(57) **CLAIM**

The ornamental design for a metering pump, as shown and described.

DESCRIPTION

FIG. 1 is a front perspective view of the metering pump of the present invention;

FIG. 2 is a rear perspective view of the metering pump of the present invention;

FIG. 3 is a top elevation view of the metering pump of the present invention;

FIG. 4 is a bottom elevation view of the metering pump of the present invention;

FIG. 5 is a right side elevation view of the metering pump of the present invention; and

FIG. 6 is a left side elevation view of the metering pump of the present invention;

FIG. 7 is a front elevation view of the metering pump of the present invention in use; and,

FIG. 8 is a rear elevation view of the metering pump of the present invention in use.

The broken lines are for illustrative purposes only and form no part of the claimed design.
